UNITED STATES PATENT OFFICE.

DAVID D. BUICK, OF LOS ANGELES, CALIFORNIA.

CARBURETER.

1,162,680.

Specification of Letters Patent.

Patented Nov. 30, 1915.

Application filed October 28, 1914. Serial No. 868,990.

To all whom it may concern:

Be it known that I, DAVID D. BUICK, a citizen of the United States, residing at Los Angeles, in the county of Los Angeles, State of California, have invented new and useful Improvements in Carbureters, of which the following is a specification.

This invention relates to a carbureter.

It is the object of this invention to provide a carbureter in which the proportions of air and volatile liquid fuel for forming an explosive gaseous mixture will be automatically regulated according to the extent of opening of a throttle disposed in the communication between the carbureter and the intake manifold of an internal combustion engine.

Another object is to provide a carbureter in which a restricted quantity of volatile liquid fuel will be drawn into the carbureting chamber together with a volume of air during the idling of the engine to which the carbureter is attached and while the throttle is in its closed position to form a charge in the carbureting chamber, and in which a volume of air is delivered to the carbureting chamber in advance of an increased quantity of the liquid fuel on opening the throttle.

Another object is to provide a carbureter having a dampered air inlet opening leading to a carbureting chamber in which the damper is opened by suction induced in the carbureting chamber and having connections operated by the damper controlling the flow of volatile liquid to the carbureting chamber according to the extent of opening of the damper, whereby fluctuations of suction such as caused by variations of drawing action of the engine pistons will be compensated for, thus insuring a uniform explosive charge being drawn into the engine cylinders.

Another object is to provide a valve mechanism for controlling the flow of volatile liquid fuel into the carbureting chamber of a carbureter which is adapted to be operated by the automatic opening of an air inlet controlling damper to proportion the air and liquid fuel according to the extent of opening of the air inlet.

Another object is to provide a carbureter of the above character comprising few simple parts which may be readily assembled and removed and which can be econom-

ically manufactured so as to produce a carbureter which can be marketed at small cost.

The invention is illustrated in the accompanying drawing, in which:

Figure 1 is a side view of the carbureter with parts broken away. Fig. 2 is a view of same in vertical section partly in elevation as seen on the line 2-2 of Fig. 1, in the direction indicated by the arrows. Fig. 3 is a horizontal section and plan view as seen on the line 3-3 of Fig. 2. Fig. 4 is an enlarged detail section and elevation on the line 4-4 of Fig. 2.

More specifically, 5 indicates the intake manifold of an internal combustion engine to which the carbureter constituting the present invention is attached by means of screws 6, and 7 indicates the upper tubular portion of the carbureter casing attached to the manifold 5. The casing 7 is formed with a cylindrical passage 8 across which a rock shaft 9 extends and mounted on the rock shaft is a disk 10 disposed across the passage 8 to form a throttle for regulating the volume of gaseous mixture drawn in to the manifold 5 from the mixing chamber of the carbureter. The throttle valve 10 is operated and its position adjusted by means of an arm 11 mounted on the rock shaft 9 and connected to any suitable operating means by which the rock shaft 9 can be actuated to dispose the throttle 10 in any desired position. The throttle is designed to not completely close the passage 8 when in its closed position, being limited in its movement in the closing direction by means of a set screw 12 threaded in a projection 13 on the arm 11 and adapted to abut against a shoulder 14 on the casing 7.

The carbureting chamber 16 of the carbureter is formed in the portion 7 below the throttle 10 and opens to the atmosphere through an intake opening 17 formed in the side of the casing member 7; the bottom walls of the mixing chamber 16 converging downwardly and terminating in a sleeve 18 having a vertically extending bore 19 adapted to receive a reciprocating valve 20. The valve 20 is tubular in form and has its open lower end projecting into a volatile liquid receiving chamber 21 formed by a casing member 22 attached to the member 7 and depending therebeneath.

The upper end of the valve 20 is formed with a restricted aperture 23 which forms a

communication between the interior of the tubular valve 20 and the carbureting chamber 16, and formed in the side walls of the valve 20 is a series of perforations 24 arranged longitudinally of the latter at suitable distances apart; the uppermost perforation 24 being normally closed by the wall of the sleeve 18 as particularly shown in Fig. 4. These perforations 24 are designed to open communication between the chamber 21 and the carbureting chamber 16 through the tubular valve member 20 when the latter is moved upwardly in the sleeve 18 so as to vary the quantity of volatile liquid drawn into the carbureting chamber in proportion to the air admitted thereto.

Extending into the carbureting chamber 16 across the inlet opening 17 is a damper 25 which normally contacts the side walls of the carbureting chamber and abuts against the inclined bottom wall 26 of the latter as shown in Fig. 2. The damper 25 is formed with an outwardly and downwardly extending arm 27 which is pivoted at its lower end to a pivot pin 28 on a plane intermediate the upper and lower edges of the damper 25 in such manner that when the arm 27 is rocked rearwardly the lower edge of the damper 25 will move on an approximately vertical plane, and thereby avoid choking or restricting the carbureting chamber. The damper 25 is normally maintained in its seated position by means of a coiled spring 29 one end of which bears against the arm 27 while the opposite end seats against a rigid bracket 30 carried by the casing member 21. The damper 25 is connected to the valve 20 in such manner that movement of the damper 25 will effect a reciprocal movement of the valve 20; the connections between the damper 25 and the valve 20 consisting of a pair of lugs 31 formed on the inner face of the damper 25 adjacent its lower end and oppositely extending studs 32 on the upper end of the valve 20 which extend into open-ended slots 33 formed on the lugs 31.

The chamber 21 communicates with a suitable source of volatile liquid supply through a nipple 34 formed on the casing member 22 and mounted in the chamber 21 is a float 35 adapted to control any suitable valve mechanism for regulating the depth of the volatile liquid in the chamber 21. A drain cock 36 is provided in the bottom of the casing member 22 to drain the chamber 21 when required.

As a means for admitting air to the carbureting chamber 16 when the damper 25 is closed to form a gaseous mixture in the carbureting chamber when the throttle 10 is in its closed position and the engine running idle an aperture 37 is formed in the damper 25 on the lower edge thereof. This aperture 37 and the opening 23 in the top of the valve 20 serve as intake openings for the

passage of air and volatile liquid into the carbureting chamber 16 when the suction in the latter is not sufficient to effect opening of the damper 25 as when the engine is running slow or idling with the throttle 10 in its closed position; the throttle 14 being normally open sufficiently to permit a slight suction occurring in the carbureting chamber when it is closed and the engine is in operation. By this arrangement on opening the throttle valve 10 an explosive mixture will be immediately drawn into the manifold 8 to charge the engine cylinders.

In the operation of the invention, when the throttle 10 is open and suction is induced in the manifold 5 a reduction of air pressure below normal atmospheric pressure will be effected in the carbureting chamber 16, thereby causing the damper 25 to move upwardly on its pivotal mounting 28 in opposition to the spring 29 thus permitting the inrush of a volume of air through the intake opening 17 into the carbureting chamber 16; the extent of opening of the damper 25 being proportional to the degree of suction induced in the carbureting chamber 16, which in turn is regulated by the extent of opening of the throttle 14 and the suction induced by engine pistons. The upward movement of the damper 25 effects a corresponding upward movement of the valve 20 so as to dispose one or more of the perforations 24 within the carbureting chamber 16, according to the extent of opening of the damper whereupon the suction induced in the chamber 16 will operate to draw a quantity of the volatile liquid from chamber 21 into the carbureting chamber 16 through the tubular valve 20 and the open perforation 23 and such of the perforations 24 as are opened to the chamber 16. By this construction the quantity of volatile liquid drawn into the chamber 16 will be proportional to the amount of air entering the carbureting chamber 16 which in turn is regulated by the extent of opening of the damper 25.

By positioning the uppermost perforation 24 so as to be normally closed by the sleeve 18 the damper 25 must be necessarily elevated a short distance before volatile liquid will be drawn into the carbureting chamber 16 through the perforation 24, thus insuring a volume of air being admitted to the carbureting chamber 16 in advance of the volatile liquid passing through the first or uppermost perforation 24; an initial charge of the volatile liquid passing through the perforation 23 and this charge being augmented by successive opening of the perforations 24 in proportion to the air admitted to the carbureting chamber. As a means for packing the valve 20 a series of annular channels 38 are formed on the lower portion of the valve which extends into the

liquid in the chamber 21, thus forming liquid packing rings.

What I claim is:

1. In a carbureter, a casing formed with a carbureting chamber having an air inlet opening, a fuel inlet opening and a mixture outlet opening, a pivoted shutter controlling the air inlet opening comprising a closure plate disposed parallel to its pivotal axis for oscillating sliding movement on its seat, a tubular piston valve extending into the fuel inlet opening and having a plurality of perforations adapted to be successively opened to the carbureting chamber, and means connecting the shutter and tubular piston valve whereby opening of the shutter will effect a reciprocating movement of the piston valve to automatically directly proportion the quantity of fuel to the volume of air entering the carbureting chamber.
2. In a carbureter, a casing formed with a carbureting chamber having an air inlet opening, a fuel inlet opening and a mixture outlet, an oscillating gate valve controlling the air inlet opening, comprising a closure plate disposed parallel to its pivotal axis, a
3. In a carbureter, a casing formed with a carbureting chamber having an air inlet opening, a fuel inlet opening, and a mixture outlet opening, a pivotal shutter controlling the air inlet opening, comprising a closure plate disposed parallel to its pivotal axis, a tubular piston valve extending into the fuel opening provided with trunnions, and having a plurality of perforations adapted to be successively opened to the carbureting chamber, and a yoke secured to the shutter provided with slots in the arms thereof in which said trunnions are disposed.

In witness that I claim the foregoing I have hereunto subscribed my name this 16th day of October, 1914.

DAVID D. BUICK.
